UNITED STATES PATENT OFFICE

WILLIAM W. DASHNER, OF LOGANSPORT, INDIANA, ASSIGNOR TO R-B-M MANUFACTURING CO., OF LOGANSPORT, INDIANA, A CORPORATION OF INDIANA

CIRCUIT BREAKER

Application filed May 31, 1929. Serial No. 367,262.

This invention relates in general to circuit breakers, more particularly to circuit breakers for the protection of electrical toys.

Electrical toys such as trains, motors and the like are usually driven by current from the commercial electric light source in the home stepped down through a suitable transformer to the voltage required to operate the device. In the case of a toy electric train, it frequently happens that the engine or cars will jump the track and establish a low resistance path from the third rail to the other rails of the track. Frequently this path is of such low resistance as to practically constitute a short circuit, and unless an arrangement is provided for disconnecting the source of current, the transformer is liable to be ruined and a fire started by this short circuit.

20 In my copending application, Serial No. 265,310 filed March 28, 1928, I disclosed a safety device for electrical toys of this kind which comprised in conjunction with the transformer supplying current to the toy, a 25 circuit breaker or relay designed to open the transformer circuit in case of an overload on the transformer. This relay may be arranged to open the primary circuit of the transformer or if desired to open the secondary 30 circuit, and the electromagnet of the relay can be placed either in the primary or secondary circuit of the transformer.

35 My present invention has for its principal object the provision of a new and improved circuit breaker of this class, adapted to be inserted in the secondary circuit of the transformer and to open that circuit when the current in it and through the circuit breaker becomes abnormally high.

40 This improved circuit breaker may be combined with the transformer in the manner indicated in the above mentioned copending application, or it may be fabricated as an article manufactured to be added to the electric train sets already in use. The combination of this relay with the transformer or other source of power for an electric train or other similar toy renders the toy safe by opening the circuit to it in case of any fault or

condition which causes an abnormally large current to flow through the breaker.

The circuit breaker built in accordance with the teachings of my present invention is of rugged construction and capable of withstanding the hard usage to which devices of this kind are subjected. Moreover the breaker can be economically manufactured and sold at an attractive price and because of its rugged construction can be expected 55 to withstand abuse and remain in an operative condition over a long period of time.

To acquaint those skilled in the art with the principle of my invention I have illustrated a preferred form of it in the accompanying drawings, in which,

Figure 1 shows a plan view of a completely assembled circuit breaker,

Figure 2 is a plan view of the breaker with the cover partially cut away,

Figure 3 is a cross-sectional view of the breaker taken along the lines 3—3 of Figure 1,

Figure 4 is an end view of Figure 1 with the cover cut away along the lines 4—4 and looking in the direction of the arrows, and 75

Figure 5 is a circuit diagram showing a use of the circuit breaker.

From the drawings, particularly Figures 2, 3, and 4 it will be seen that the breaker comprises the base plate 1 upon which is 80 mounted the sub-base 2. The sub-base 2 is preferably made of an insulating material such as a phenol condensation product or a fiber. Attached to the sub-base 2 are the L-shaped bracket 11, the Z-shaped bracket 14, and the C-shaped bracket 19. These brackets are all preferably made of magnetic iron, although if desired bracket 19 may be made of any other preferred metal.

The electromagnet 10 is attached to the upper end of the L-shaped bracket 11. This magnet comprises the magnetic iron core 12 around which are placed the customary spool heads to retain the copper wire winding in place on the core. In the preferred embodiment of the invention this winding will be of very low resistance since it will be connected in series with the circuit extending to the toy protected by the breaker. Preferably the winding is of enameled copper wire 100

although any other preferred form of installation may be used.

The armature 15 is supported at approximately its mid point by the pivot screw 16 which projects through it and the Z-shaped bracket 14. One end of the armature, that is the end adjacent to the electromagnet 10 is equipped with the downward projecting pole piece 17 which engages the pole piece of the electromagnet 10 when the armature is in its energized position.

The magnetic circuit of the armature and electromagnetic extends from the core of the magnet 10 through the air gap into the pole piece 17 of the armature, through the armature and pivot into the bracket 14 and across another air gap disposed between the foot of the bracket 14 and the foot of the magnet supporting bracket 11. The air gaps in this magnetic circuit are large and consequently a high magnetization of the core 12 is necessary before sufficient strength will be developed to attract the armature 15, and in the normal operation of the toy the current drawn by it will not be sufficient to produce this magnetization of the core.

The other end of the armature 15 extends into juxtaposition to the C-shaped bracket 19. A contact spring 18 is attached to the upper portion of this bracket and extends downward to a point below the plane of the armature 15, and then upward into engagement with the bottom side of that armature. This spring extends beyond the point of contact with the armature in a downward direction at an angle as will be best seen in Figure 4, for a purpose which will be hereinafter pointed out.

A projecting lip 20 is bent upward from the upper arm of the bracket 19 in a plane substantially vertical to the sub-base 2. An operating lever 21 is pivoted to this bracket, this lever having a projection 22 which projects through an opening 23 in the armature 15. Through the operation of this lever the circuit through the circuit breaker is reclosed after it has been opened by an overload. The lever 21 is preferably made of an insulating material such as a phenol condensation product or a fiber to guard against the possibility of the operator receiving a shock from the lever when it is being moved to close the circuit through the breaker.

A metallic box-like cover 3 is attached to the base plate 1 and serves to enclose the breaker mechanism. This cover is provided with a slot through which the lever 21 extends to permit the operation of that lever to reset the breaker without removing the cover from the breaker. Terminal posts 30 and 31 are mounted in the end of the cover and insulated therefrom by the insulators 50. Preferably the cover is made of sheet iron and formed out of one piece in a forming press. The cover is finished by lacquer pref-

erably of a color such as red which is most attractive and conspicuous. The cover is held on to the base either by the bolt 4 extending through the ears 3' of the cover and corresponding projections of the base, or by an eyelet placed through these parts.

One of the terminals 31, is connected by the wire 33 to one end of the coil 10, and the other end of that coil is connected by the wire 34 to the bracket 14 where it is attached at 35 either by soldering or by any other preferred method.

The electrical circuit continues through the bracket 14 and the armature 15 and the contact spring 18 to the bracket 19 which is connected by the wire 32 to the other binding post 30. It will be noted that the electromagnet 10 and the contacts 15 and 18 are in a series circuit extending through the circuit breaker from binding post to binding post.

Figure 5, illustrates a use of the circuit breaker. In this circuit the breaker is connected in a series with the secondary circuit of a transformer used for driving electrical toys and the like. The primary winding 44 of this transformer is connected to a commercial lighting circuit which is usually of 110 volts, 60 cycle alternating current. The secondary winding 43 is magnetically coupled to the primary winding by the core 45 and terminates in the terminals 40 and 41. The terminal 41 is connected through the variable rider 42 which engages the secondary winding at various points to adjust the voltage in the secondary circuit. As shown the terminal 40 of the transformer is connected to terminal 31 of the circuit breaker, the circuit extending through the winding of the magnet 10, through the armature 15 and the contact 18 to the terminal 30 of the circuit breaker from whence it goes through the electrical toy and returns to the transformer through the terminal 41.

Assume the electrical toy in Figure 5 is an electrical train, while that train is on the track and running normally the current flowing through the secondary circuit will not be sufficiently strong to attract the armature 15. It will be noted in Figure 4, that the spring 18 bears against the under flat surface of the armature 15, this spring having considerable tension places an appreciable friction upon the armature which must be overcome by the electromagnet before the armature can be moved. As long as the train stays upon the track the current through this circuit will not generate sufficient flux in the magnet 10 to overcome this friction and attract the armature.

If however the train goes off the track and thereby short circuits the secondary circuit, the current therein and through the electromagnet 10 will rise to such a value that the magnetomotive force of the magnet will be

sufficiently high to drive a larger amount of flux across the air gaps of the magnetic circuit to overcome the friction of the spring 18 against the armature 15 and to move that armature into engagement with the pole piece 12.

It will be noted in Figure 4, that the portion of spring 18 extending beyond the point of contact of that spring with the armature 15 angles downward. When the magnet 10 attracts the armature 15 and moves it to the left in Figure 4 this angling portion of the spring will bear against the edge of the armature and impart thereto a force tending 15 to move the armature to the left.

By this arrangement the tension of the spring 18 is first made to oppose the movement of the armature and later when that movement has actually started this same tension is employed to assist the movement.

The slope of the spring 18 is such that the tension of it is applied to the armature until the pole piece 17 of the armature is quite close to the pole piece 12 of the electromagnet 10 and since the force of the electromagnet 10 upon the armature pole piece 17 varies inversely as the square of the distance between the two, this force will be high when the tension of the spring is removed from 20 the armature, and the armature will be moving at a high rate of speed. The current will be broken only when the edge of the armature 15 moves out of engagement with the sloping portion of spring 18, and since the 25 armature is moving at a rapid rate when this occurs the breaking of the circuit will not result in an appreciable arc even though the current broken is quite large. Moreover by this arrangement the surfaces through 30 which the current is normally conducted are not surfaces through which the current is passing when the circuit is opened, and any arcing which may pit the breaking surface will have no effect upon the normal circuit 35 through the breaker.

When the armature moves to the left as seen in Figure 4, the lever 21 rotates about its pivot and that portion of it extending beyond the cover 3 moves to the right in the 40 slot in the cover. This altered position of the lever 21 serves as a signal or indicator to apprise the operator that the circuit breaker has opened.

After the train has been replaced on the 45 track and it is desired to again supply current to it the lever 21 is moved to the left as seen in Figure 4, to thereby rotate the armature 15 in the opposite direction to reestablish the connection between it and the spring 18 to thereby reclose the circuit through the breaker.

From the foregoing it will be apparent that the use of this circuit breaker opens the circuit to an electrical toy or similar device 50 when the current flowing thereto becomes ex-

cessively large and moreover the open position of the circuit breaker is indicated by a visual signal. The device is ruggedly constructed and can be economically made.

While I have chosen to draw a preferred embodiment of my invention, I have done so by way of example only as I am aware that there are many modifications and adaptations which can be made within the scope of the invention and I am not therefore to be limited by the specific disclosure made.

Having thus complied with the statutes as shown and described a preferred embodiment of my invention, what I consider new and desire to have protected by Letters Patent, is pointed out in the appended claims.

What is claimed is:

1. In a circuit breaker of the class described, an armature, a magnet coil, a pivot about which said armature is moved by an abnormal energization of said magnet coil, a spring engaging said armature, and an angled extension of said spring engaging said armature only during its rotation about its pivot to aid said rotation.

2. In a circuit breaker of the class described, an armature, a magnet coil, a pivot about which said armature is moved by an abnormal energization of said magnet coil, a contact spring engaging said armature to establish an electrical circuit through it and said coil, and an angled extension of said spring engaging said armature only during its rotation about its pivot to aid said rotation.

3. In a circuit breaker of the class described, a pivoted armature moved in one direction by an electromagnet, a contact spring normally engaging a flat face of said armature, and an inclined extension of said spring which engages the edge of said armature while it is being moved by the electromagnet to cause the tension of said spring to assist in said movement.

4. In a circuit breaker of the class described, a pivoted armature moved in one direction by an electromagnet, a contact spring normally engaging a flat face of said armature, said spring containing an extension shaped to resist movement of said armature until such is started and then to aid that movement.

5. In a circuit breaker of the class described, a pivoted armature moved in one direction by an electromagnet, a bracket disposed adjacent one end of said armature and having an extension disposed above it, a contact spring attached to said extension, said spring extending downward through an arched path then upward into engagement with the under surface of the armature and finally downward from the point of contact with the armature, said final portion bearing

against the edge of the armature during its movement to aid in that movement.

6. A circuit breaker comprising, a base, a sub-base of insulating material mounted thereon, an L-shaped magnetic iron bracket attached to said sub-base, an electromagnet mounted on said bracket, a Z-shaped magnetic iron bracket mounted on said sub-base, an armature pivoted thereon, one leg of said Z bracket being spaced adjacent said L bracket to form with said armature a low permeability magnetic path for said electromagnet, and contacts closed and opened by said armature.

15 7. A circuit breaker comprising a base, a sub-base of insulating material mounted thereon, an L-shaped magnetic metal bracket attached to said sub-base, an electromagnet mounted on said bracket, a Z-shaped magnetic metal bracket mounted on said sub-base, an armature pivoted thereon, one leg of said Z shaped bracket being disposed adjacent said L bracket to form with said armature a low permeability magnetic path for said 20 electromagnet, a C-shaped bracket on said sub-base, a contact spring mounted thereon and cooperating with said armature to establish an electrical contact therebetween, and a lever mounted on said C-bracket and 25 engaging said armature to move it.

8. A circuit breaker of the class described, comprising a base, an insulating sub-base mounted thereon, a coil, an armature, and a contact spring, a separate bracket for mounting each on said sub-base, said coil and armature bracket with the armature forming a low permeability magnetic path for said coil, a cover mounted on said base to enclose said breaker, and a lever mounted in juxtaposition to said armature and contact spring and extending through a slot in said cover.

In witness whereof, I hereunto subscribe my name this 22nd day of May, 1929.

WILLIAM W. DASHNER.
